United States Patent Office.

ALPHONSO W. COOK AND ROBERT DEMPSTER, OF BUFFALO, NEW YORK,
ASSIGNORS TO THEMSELVES AND J. S. SEMON, OF SAME PLACE.

Letters Patent No. 78,788, dated June 9, 1868.

IMPROVEMENT IN HYDROCARBON-BURNERS.

The Schedule referred to in these Letters Patent and making part of the same.

TO ALL WHOM IT MAY CONCERN:

Be it known that we, ALPHONSO W. COOK and ROBERT DEMPSTER, of the city of Buffalo, county of Erie, and State of New York, (assignors to ourselves and J. S. Semon, of the same place,) have invented a certain new and improved Petroleum-Gas Furnace; and we do hereby declare that the following is a full, clear, and exact description thereof, reference being had to the accompanying drawings, making a part of this specification, in which—

Figure I is a vertical section.

Figure II is a top plan view.

Figure III is a transverse vertical section.

The nature of this invention consists—

First, in the construction and use of a retort, having upon the inside thereof a coil of pipe connected to the feed-tube, in combination with a common heating-furnace.

Second, in a retort for generating gas from petroleum, having a cored bottom with an air-supply pipe.

Third, in a retort for generating gas from petroleum, having a removable bottom plate, by means of which sand or other sediment of the petroleum may be readily removed.

Fourth, in a retort for generating gas from petroleum, having upon the inside thereof an open pan attached to the feed-pipe, and a discharge-pipe connected thereto, by means of which the tar or other sediment of the heavier quality of petroleum is collected and carried off.

Fifth, in the construction and use of a metallic plate forming the top of a gas-generating furnace, which plate has one or more openings, for the suspension therein of one or more retorts, and a number of apertures for the introduction of the fuel.

Sixth, in the construction, application, and use of a feed-regulating chamber, and a strainer, the said chamber being adjusted to the feed-pipe, and provided with hollow plugs or bushings for enlarging or diminishing the size of the bore of the feed-pipe, and regulating the feed.

Seventh, in the combination, with a retort for generating gas from petroleum, of a force-pump, which is attached to the feed-pipe, and may be used either for pumping petroleum into the retort (in case feeding by atmospheric pressure is inconvenient or impracticable) or for forcing water into the retort for the purpose of generating steam therein.

Eighth, the application and use of the herein-described apparatus for generating steam for heating and other purposes.

Letters of like name and kind refer to like parts in each of the figures.

A represents a retort, which is suspended within the fire-chamber of a furnace by means of the top flange, a^1 . The furnace B may be built of brick or cast iron, and is divided, by means of suitable partitions, into as many separate fire-chambers as there are retorts, so that the fire surrounding each retort may be fed and regulated separately. There may be one, two, or more fire-chambers and retorts, connected as shown in the drawings. Each fire-chamber has a drop-grate, b^1 , as shown in Fig. III, which renders the introduction of kindling and the starting of the fires more convenient.

The top of the furnace consists of a cast-iron plate, C, which is provided with openings, C^1 , for the suspension therein of the retorts and apertures C^2 , with covers, C^3 , for the introduction of the fuel. This top plate, C, may be made either in sections of the size of each fire-chamber, or in one piece, covering two or more fire-chambers, as represented in the drawings.

The retort A is provided with a cover, D, which is fitted on to the top thereof, and secured by means of the key d^1 , passing through the two slotted standards d^2 , erected upon the flange a^1 . The cover D, as well as the opening in the retort, is made bevelled, so that a more perfect and air-tight connection may be made. A draught-flue E is formed upon the top of the plate C, at a point where communication can be established with

all the fire-chambers. Dampers, E¹, are placed therein, for regulating the fire in each chamber independent from the others. The smoke-stack E² is connected to this draught-flue, as shown in the drawings.

F represents the feed-pipe, by means of which the petroleum is conveyed into the top of the retort. It passes through the cover, D, and a coil of gas-pipe, G, is connected to it upon the inside of the retort.

For the lighter qualities of petroleum, such as gasoline, &c., this coil of pipe serves the purpose of converting the fluid into a vapor before it issues from the end of the pipe. When a heavier quality of petroleum is to be used, the coil of pipe is removed, and a dripping-pan, H, attached, which catches all of the fluid; and as the tar or other sediment sinks to the bottom, it is carried off through the discharge-pipe H¹.

I represents the feed-regulator and strainer, which is contained in an air-tight chamber, having a removable cover, which chamber is connected to the feed-pipe, as shown at Fig. I. The feed is regulated, according to the capacity of the retort, with a given amount of heat, by means of hollow plugs or bushings, i¹, which are inserted into the open end of the feed-pipe upon the inside of the chamber, as shown.

J represents a wire-gauze partition, placed diametrically within the chamber I, which serves the purpose of straining the fluid passing through said chamber, and retaining all coarse dirt, sand, or other foreign matter.

The main pipe, which carries the gas generated in the retort into a gasometer, and thence into the building, is shown at K, and has a stop-cock, k¹. It is connected to a blow-off pipe, L, having a stop-cock, L¹, upon its end, which blow-off pipe is used for the purpose of cleaning the retort, as herein described.

M represents a false bottom, which is placed within the retort, and provided with a ring or handle, m¹, by means of which it may be lifted out through the opening at the top. This is used for the purpose of facilitating the cleaning of the retort. The most of the sediment of petroleum consists of a fine sandy substance, which settles upon the bottom, and if received within the false bottom, M, may be easily removed.

The bottom proper of the retort is cored out, an annular opening being formed as shown at n, which has an outlet at n¹. A continuous current of air passes through the opening, which has the effect of preventing the wear of the bottom of the retort from excessive heat. The discharge-spout, for the escape of the gas into the main pipe, is shown at O, and is cast on to the retort, as is also the outlet n¹, extending outwardly through the brick wall of the furnace.

P represents a force-pump, which is connected to the feed-pipe upon that side of the chamber I which is opposite the bushing, i¹. This pump, in connection with the blow-off pipe L, may be used for cleaning the inside of the retort, as follows: Close the stop-cocks k¹ in the main pipe, and X in the feed-pipe, and open the stop-cock L¹ in the blow-off pipe; then place a basin of water under the pump, so as to immerse the lower portion thereof, (as shown by red lines in Fig. I,) and slowly force a fine stream of water into the retort. Steam is generated instantaneously, the force of which drives all fine sand or other sediment through the only outlet, the blow-off pipe L.

In the drawings we have represented a furnace large enough for four retorts, but we can also use one, two, or more retorts, according to the amount of gas to be generated. In case one or all of the retorts are not used for making gas, they can be used for generating steam without removing or altering any portion of the apparatus herein shown and described.

What we claim as our invention, and desire to secure by Letters Patent, is—

1. The coil of pipe, G, in combination with the feed-pipe F and retort A, arranged and operating substantially as and for the purpose described.

2. The dripping-pan H and discharge-pipe H¹, in combination with the feed-pipe F and retort A, for the purpose and substantially as described.

3. The plate C, having openings C¹ and C², in combination with the furnace B, draught-flue E, and retort A, constructed and arranged substantially as herein set forth.

4. The removable bottom plate M, in combination with the retort A, for the purpose and substantially as herein described.

5. The annular air-chamber n and outlet n¹, in combination with the retort A, for the purpose and substantially as herein described.

6. The chamber I, plugs or bushings i¹, and strainer J, in combination with the feed-pipe F, for the purpose and substantially as herein described.

7. The combination of the force-pump P, feed-pipe F, and blow-off pipe L, for the purpose of cleaning the inside of the retort A, substantially as described.

8. The application and use of the apparatus herein described, for generating steam, in the manner and for the purposes substantially as herein set forth.

A. W. COOK,
R. DEMPSTER.
